UNITED STATES PATENT OFFICE.

HARRY BUDD, OF INDEPENDENCE, KANSAS.

WASHING-MACHINE.

1,098,555.

Specification of Letters Patent.

Patented June 2, 1914.

Application filed April 29, 1912. Serial No. 693,976.

To all whom it may concern:

Be it known that I, HARRY BUDD, a citizen of the United States, residing at Independence, in the county of Montgomery and 5 State of Kansas, have invented certain new and useful Improvements in Washing-Machines; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to washing machines, and more particularly to a device adapted for attachment to an ordinary wash bench, and for movement into and from a tub supported on the bench, so that it may be used 20 when desired and when not in use may be turned back out of the way of the laundress, the object of the present invention being to provide a convenient and portable supporting arm for swinging and supporting the 25 washing device. In accomplishing this object, I have provided the improved details of structure hereinafter described and illustrated in the accompanying drawings, wherein:—

30 Figure I is a perspective view of a wash bench and a washing device mounted on the bench by my improved supporting means, parts of the wringer with which the bench is equipped being omitted to better disclose the 35 supporting means. Fig. II is an enlarged vertical section of part of the washing device showing the supporting means holding the washing device in idle position. Fig. III is an enlarged perspective of one of the 40 supporting arms and a part of the washing device, showing the connection of these parts.

Referring more in detail to the parts:— 1 designates a wash bench of any ordinary 45 construction and equipped with a wringer which is partially illustrated at 2, one of the wringer rollers having a shaft 3 extending through the bench standards and journaled therein, one end of the shaft being 50 equipped with a handle 4 by which the wringer is operated.

55 5 indicates the washing device which is adapted for projection into the top of the ordinary washtub 6 when the latter is supported on the bench, and comprises a base 7 having vertical supports 8 and 9 adapted for

sliding travel relative to each other, and end flanges 10. On the support 8 are rollers 11 and on the support 9 is a pressure roller 12, the latter roller being preferably corrugated in order to beat against the other rollers when the device is in operation. The large roller 12 has a shaft 13 adapted for revolution in slotted bearings in the supports 8 and 9 and has a handle 14 by which it may be revolved, the shaft fitting loosely within its bearing and being held to the base 6 by spring posts 15, having grooves 16 whereby the members are adapted for projection over the shaft to hold same to the 70 frame.

17 designates the supporting arms which are preferably formed of strap metal, each stamped to provide a slot 18, a laterally offset head 19, having a base 20, extending 75 diagonally across the body of the arm, an attaching flange 21 extending at a right angle to the body of the arm and a concaved seat 22 at the end opposite the attaching flange. The arms are adapted for mounting 80 on the bench by projecting ends of the wringer shaft 3 through the slots 18, so that one of the arms will be mounted at each end of the wringer, and by screwing, or otherwise attaching the flanges 21 to the ends 10 85 of the base of the washing device, as illustrated most clearly in Fig. III.

With the parts arranged as described, the arms may pivot on the wringer shaft and may slide longitudinally thereon to extend 90 the washing device laterally from the wringer, or to move the same thereto by sliding the arms over the wringer shaft, the inner faces of the bench standards being provided with pins 23 which may connect the 95 parts of the wringer with the bench and serve as supports for the arms, when the concaved lower ends of the latter are lowered thereagainst in order to support the washing device above the wringer but in close relation thereto.

When the device is not in use, the arms 17 are arranged vertically on the bench standards, with the concaved seats 22 supported on the bench pins 23, in which position the 105 upper ends of the slots will be close to the wringer shaft, and the washing device supported at the top of the wringer, in order that the entire apparatus may occupy the least possible space.

When the washing device is to be used, the bench is set up and a tub placed on one

end thereof. The washing device is then lifted slightly to unseat the arms, and the arms are then pivoted on the wringer shaft and moved longitudinally thereon to extend 5 the device into the tub where it is supported by the arms resting on the edge of the tub. The washing device may then be used in the ordinary manner, and when the washing is finished, or when it is desired to remove the 10 device from the tub, the device may be raised and returned to its original position by sliding the arms on the wringer shaft and lowering same thereon reversely to the action heretofore described.

15 By providing the arms with the offset portions, the arms may be mounted inside of the wringer standards and on the outer faces of the washing device supports so that the offset portions of the arms may bear against 20 the device supports and brace the attachment, the diagonally arranged offsets allowing the washing device to drop at an angle to the bench when in idle position and thereby occupy less space than if the device were 25 extended vertically or horizontally.

Having thus described my invention, what I claim as new therein and desire to secure by Letters-Patent is:—

Claims.

30 1. The combination with a washer, of

slotted arms connected with the washer, supporting standards having a shaft projecting through the arm slots, whereby the arms are supported by and adapted for sliding travel on said shaft, and means on said standards 35 for engagement by said arms to support the latter in vertical position.

2. The combination with a washer, of slotted arms having their outer ends connected with the washer and having concave 40 seats in their inner ends, standards having a connecting shaft projected through the slots in said arms and upon which the arms are adapted for guided travel, and pins on said standards upon which the concave seats are 45 adapted to rest when the arms are in vertical position.

3. The combination with a washer, of suitable standards, arms having outset end heads overlying and connected with the 50 outer ends of said washer, and having sliding support at the inner sides of said standards, and means on said standards for supporting the arms in vertical position.

In testimony whereof I affix my signature 55 in presence of two witnesses.

HARRY BUDD.
